Primary Examiner — Kelley Donnelly(74) *Attorney, Agent, or Firm* — Seed IP Law Group PLLC(57) **CLAIM**

The ornamental design for a green wall frame, as shown and described.

DESCRIPTION

FIG. 1 is a perspective view of a green wall frame showing a first embodiment of my new design;

FIG. 2 is a front elevational view thereof.

FIG. 3 is a left side elevational view thereof.

FIG. 4 is a right side elevational view thereof.

FIG. 5 is a rear elevational view thereof.

FIG. 6 is a top plan view thereof.

FIG. 7 is a bottom plan view thereof.

FIG. 8 is a perspective view of a green wall frame showing a second embodiment of my new design;

FIG. 9 is a front elevational view thereof.

FIG. 10 is a left side elevational view thereof.

FIG. 11 is a right side elevational view thereof.

FIG. 12 is a rear elevational view thereof.

FIG. 13 is a top plan view thereof; and,

FIG. 14 is a bottom plan view thereof.

The broken lines in the figures are for illustrative purposes only and form no part of the claimed design.
